UNITED STATES PATENT OFFICE.

THEODORE METZELER, OF BROOKLYN, NEW YORK.

DESIGN FOR A MOTTO.

SPECIFICATION forming part of Design No. 22,866, dated November 7, 1893.

Application filed September 16, 1893. Serial No. 485,733. Term of patent 3½ years.

To all whom it may concern:

Be it known that I, THEODORE METZELER, a citizen of the United States, residing at Brooklyn, in the county of Kings and State of New York, have invented and produced a new and original Design for a Motto, of which the following is a specification, reference being had to the accompanying drawings, forming part thereof.

10 My design is for a package containing usually a paper cap, a snapper, and a motto or quotation, used as a favor at social functions and commonly called a "motto."

15 Figure 1 is a front view of my newly designed motto. Fig. 2 is a rear view of the same.

The leading feature of my design consists of a dressed doll-like figure on the front of the body of the package, which body falls within

the outlines of, and is concealed from front view by the doll-like figure, as indicated in Fig. 1. The body of the package is shown in Fig. 2, and is of cylindrical shape, ornamented at the ends with spreading tassels. The doll-like figure is arranged longitudinally on the front of the package-body, is dressed, and with its garment completely conceals the package-body from front view, the body falling within the outlines of the dressed figure.

What I claim is—

20 The design for a "motto" substantially as 30 herein shown and described.

THEODORE METZELER.
